CLAIM

The ornamental design for a hair color solution applicator, as shown and described.

DESCRIPTION

FIG. 1 is a top plan view of the hair color solution applicator showing my new design;

FIG. 2 is a bottom plan view of the invention thereof;

FIG. 3 is a side elevation view thereof;

FIG. 4 is an elevational view of the side opposite FIG. 3;

FIG. 5 is an end view thereof;

FIG. 6 is an elevational view of the side opposite FIG. 5; and,

FIG. 7 is an elevation view of the invention attached to a bottle.

The broken line showing of the bottle in FIG. 7 is for illustrative purposes only and forms no part of the claimed design.
